UNITED STATES PATENT OFFICE.

HARRY M. DENYES, OF SAGINAW, MICHIGAN, ASSIGNOR TO GENERAL MOTORS CORPORATION, OF DETROIT, MICHIGAN, A CORPORATION OF DELAWARE.

HORN BUTTON.

Application filed February 15, 1926. Serial No. 88,338.

My invention relates to switches and more particularly switches for horns.

One of the objects of my invention is to provide a practical horn button switch of simple and inexpensive construction, free of rattle, of simple assemblage and positive in operation. Other objects of my invention will appear hereinafter.

My invention consists in the novel arrangement and construction of parts as hereinafter more particularly described in the following specification and pointed out in the annexed claims.

In the accompanying drawing:

Figure 1 is a fragmentary view of the upper end of a steering column illustrating a device mounted thereon which embodies the features of my invention.

Figure 2 is a sectional view taken on Figure 1 at the plane of the line 2—2 and looking in the direction of the arrows.

Figure 3 is a side elevation of the S shaped ring shown in Figure 2.

Figure 4 is an enlarged sectional view taken at the plane of the line 4—4 on Figure 1.

Like numerals of reference indicate similar parts throughout the different figures.

My device is adapted to be mounted on the steering column of an automobile of any of the usual types.

Keyed to the upper extremity of the steering column 4 is the steering wheel 5 locked thereon by the nut 6. A tube 7 extending upwardly through the said column 4 carries a housing 8 composed of upper and lower supporting plates 9 and 10, the said housing having mounted thereon actuating levers 11 and 11^a.

Formed on the upper supporting member 10 is a hollow boss, or cylindrical extension 12 which encloses and supports the contact mechanism 13, which preferably comprises a button 14, a bridge or ring support 15, an insulation block 16 in which is embedded a hollow conducting member 17 and a resilient member or spring 18.

The various parts assume preferably the construction and shape as shown in the drawing, that is, the button head 19 is shaped to provide a suitable annular groove 20 surrounding the boss 21 to receive the upper surface of the said boss 12. The boss 21 of the button head has embedded therein a suitable fastening device such as a hollow

rivet 22. A guiding member 23, having a relatively large diameter, may be fashioned preferably after the manner disclosed in Figure 1, and it will be seen that the peripheral surface of this said member is adapted to slide within the bridge 15, and thus guide the actuating button.

The bridge 15 comprises a circular ring formed with a depending supporting arm 25, in this instance, integral with the ring. 60 The said supporting arm 25 is conveniently provided with a threaded aperture 26 to receive the set screw 27 fitted in a countersunk aperture 27^a in the hollow boss 12 for the purpose of clamping the said bridge 15 in 65 position. The bridge 15 is conveniently formed with a pair of depending tabs 28 and 28^a which extend through suitable slots formed in the block 16 and the spring 18 for receiving them, and are folded inwardly against the block to rigidly attach the block and the spring 18 to the said bridge. The said spring 18 preferably assumes the shape of the letter S. As will be seen in 70 Figure 3, there is provided a flat central 75 elevated portion 29 supported by a pair of resilient arms 30. There is formed in the elevated portion 29 a suitable aperture 30^a to receive the extended end of the said rivet 22.

The insulation block 16 preferably assumes the shape of a rectangular block formed with curved ends conforming substantially with the contour of the hollow boss 12. A threaded aperture is conveniently 80 provided through one side of the conducting member 17 and the material of the insulation block therearound may be so shaped as to provide a clear space surrounding the clamping screw 31 which effects an electrical connection between the wire 32 and the said conducting member 17. By the above arrangement, it will be seen that when the conducting member is grounded against the boss 12 of the supporting plate 10 the 85 circuit of the horn will be closed. By reason of the relatively long bearing of the ring support and the relatively large sliding surface of the guiding member 23, no tilting or 90 rocking of the horn button will be experienced; and yet a thrust imparted to the button off the center line will actuate the horn.

From the foregoing it will be seen that I have made a construction, disposition and combination of various parts which will 95

fully attain the objects hereinbefore set forth. Modification of the above may be made within the spirit and scope of my invention.

5. What I claim is:

1. A switch comprising a base of insulation material, a stationary contact member carried thereby, a guide of relatively extended guiding surface mounted over the 10 said base, an actuating member slidably mounted in the guide, and an **S** shaped spring inter-connected between the said guide and the last named member adapted to normally urge the said actuating member 15 into inoperative position.

2. A circuit breaking mechanism including a base of insulation material, a stationary contact member, a movable contact member, a guide ring, a guiding member slidably mounted in the said ring and carrying the said movable contact having a relatively extended, and broad guiding surface to adapt the said movable contact member to be actuated by thrusts imparted off the center 25 line of the said member, and an **S** shaped spring normally urging the said movable contact member into inoperative position.

3. In a switch, the combination of a housing, a ring support mounted in said housing, an actuating member slidably mounted in said ring support, a central conducting member secured within the said housing and resilient means clamped to the said actuating member and the said ring support, to maintain normally a spaced relation between the said conducting member and the said actuating member.

4. In a switch, the combination of a housing, a ring support mounted in said housing, an actuating member slidably mounted in said ring support, an insulation block carried in the said housing, a central conducting member embedded therein, and a resilient member having a peripheral portion clamped over the said block and a central portion fastened to the said actuating member.

5. In a switch, the combination of a housing, a bridge mounted across the said housing comprising a ring support, an actuating member slidably mounted in said ring support, an insulation block carried underneath

the said bridge, a central conducting member embedded in the said insulation block, clamping means associated with the said conducting member for effecting an electrical contact with the said member, a resilient member to urge the said actuating member upwardly out of contacting relation with the said central conducting member, means associated with the 60 said bridge to support the outer portion of the said resilient member and means associated with the said actuating member for clamping the central portion of the said resilient member thereunto. 65

6. In a switch, the combination of a housing, a bridge mounted thereacross comprising a ring bearing, an actuating member slidably mounted in the said bearing comprising a button head formed with an annular groove adapted to receive the upper surface of the said housing and formed with a central boss having embedded therein a fastening implement, a guiding member adapted to fit over the said boss, a resilient member comprising an **S** shaped spring having an elevated portion clamped to the said guiding member by means of the aforesaid fastening implement, means associated with the said bridge to retain the bottom portion 70 of the said resilient member in fixed relation with respect to the said bridge, an insulation base carried in the said housing, a central conducting member embedded therein, and means carried in the said conducting member for establishing an electrical contact therewith. 75

7. A circuit breaking mechanism including a housing, a bridge support mounted in the said housing, an insulation block disposed in the said housing, a central conducting member embedded in the said block, means to establish an electrical contact with the said conducting member, an actuating member provided with a wide elongated 80 guiding surface having a diameter substantially equal to two-thirds of the diameter of the said housing and adapted to engage an elongated bearing of the said bridge and an **S** shaped spring urging normally the said 85 actuating member into inoperative position. 100

In testimony whereof I affix my signature.

HARRY M. DENYES.
